UNITED STATES PATENT OFFICE.

JAMES NEWBY AND THOMAS F. NEWBY, OF HARRISBURG, PENNSYLVANIA.

PURIFIER AND AERATOR.

SPECIFICATION forming part of Letters Patent No. 530,445, dated December 4, 1894.

Application filed February 13, 1894. Serial No. 500,056. (No model.)

To all whom it may concern:

Be it known that we, JAMES NEWBY and THOMAS F. NEWBY, both of Harrisburg, in the county of Dauphin and State of Pennsylvania, have invented a new and Improved Purifier and Aerator, of which the following is a full, clear, and exact description.

Our invention relates to improvements in that class of machines which are used especially in connection with flouring-mills to separate the dust, fluff, &c., from middlings, break-stock and other flour stock, and in that class of machines used to aerate flour or flour stock; and the object of our invention is to produce a simple and inexpensive apparatus designed for such purposes, which apparatus uses air taken from beyond the walls of the building, purifies such air by straining through cloth and handles such pure air in a way to remove from the stock acted on thereby, the dust, fluff, and impurities and at the same time dries, cools and bleaches the stock, causing the stock to bolt more freely in the mill, and in case of flour, causing it to pack better, keep better and absorb more water in baking; the apparatus being adapted to act on a continuous stream of stock as it is passed through it.

To these ends our invention consists of certain features of construction and combinations of parts, which will be hereinafter described and claimed.

Reference is to be had to the accompanying drawings, forming a part of this specification, in which similar figures of reference indicate corresponding parts in all the views.

Figure 1 is a sectional elevation of the apparatus embodying our invention. Fig. 2 is a sectional plan on the line 2-2 of Fig. 1. Fig. 3 is a vertical section on the line 3-3 of Fig. 1, showing in detail the arrangement of the first dust chamber where the outside air is admitted and purified. Fig. 4 is a vertical section on the line 4-4 of Fig. 1, showing the arrangement of the second dust chamber and the conveyer for carrying away the dust and fluff; and Fig. 5 is a detail sectional plan on the line 5-5 of Fig. 1.

The apparatus is provided with a main case 10, which may be of any approved construction and which has a hopper-like bottom 10^a terminating in a discharge spout 10^b.

The case is supported on a suitable framework 11 and at one side of the case is a purifier 12 which has an inlet pipe 13 delivering into a space 14 at the top of it, this pipe 13 being adapted to extend through the building in which the purifier is located and to receive its air supply from out of doors.

In the central portion of the purifier case 60 is a series of vertically arranged cells 15, made of cloth, through which the air may pass, these cells being supported on suitable cross bars 16 and 17 at their upper and lower ends, and thus a plurality of narrow channels, open only at the top and bottom, is formed through which the air passes as it is drawn into the machine. Beneath these cells is a dust chamber 18, in which the dust may settle, and access to the main case and to the dust chamber is had by means of doors 19 and 20.

The air is drawn from one side of the purifier 12 through a pipe 21, by means of a fan 22 of ordinary construction, which is carried by a shaft 23 beneath the purifier, this shaft having a suitable driving pulley 24, although any means may be employed for turning it. The fan causes the air to rush in through the pipe 13 and down through the purifying cells 80 15, to the cloth of which the dust, smoke, and other impurities stick, so that the air which issues from the purifier passes to the main case freed from all impurities, cooled and in condition to have the most beneficial effect 85 on the stock with which it comes in contact, as specified presently.

By reference to Fig. 3 it will be seen that the cells 15 hang downward in the purifier case 12, air spaces being left at the sides so 90 that the air passes through the cloth of the cells and down through the pipe 21, while the dust which drops from the cells collects in the chamber 18.

The air exhausted from the purifier by the 95 fan 22 is delivered into the lower portion of the main case 10 and through a pipe 25, which has an upturned end 26 which is closed at the top and in the sides of which are ports 27 through which the air passes, these ports 100 being arranged circumferentially around the upturned end of the pipe so that the air issues from all sides thereof, as indicated by the arrows in Fig. 1. Above the pipe 25 is a

revolving deflector plate 28, on which the stock is delivered, and the stock is thrown off the edges of the plate in a sort of spray through which the pure air passes as it issues through 5 the ports 27, and thus every particle of the stock is subjected to the influence of the pure air and is thoroughly dried, cooled, and separated from the dust, fluff, &c.

The stock is fed upon the deflecting plate 10 from a chute 29 arranged vertically in the case 10 and enlarged preferably at its upper end, as shown at 30. A continuous stream 15 of stock is delivered into the chute from the feed spout 31 above the case. In the lower end of the chute 29 is a vertical revoluble shaft 32, carrying radial arms 33 which serve as agitators and distributers and cause the stock to drop stably upon the deflecting plate 28 and fall evenly off its edge. It will 20 be seen that this arrangement spreads the stock so that the air has the best possible chance to strike every particle of it.

The shaft or spindle 32 of the agitator and plate has, at its lower end, a pinion 34 which 25 meshes with a pinion 35 on a horizontal shaft 36, which shaft is held in a suitable casing 37 and projects outward through the main case 10, and it is driven by a belt 37^a, from the shaft 23, as shown in Fig. 2, but such shaft 30 or spindle 32 may be driven by any suitable means. Leading from the upper portion of the case 10 is a pipe 38, which connects with a fan 39, and the discharge pipe 40 of this fan delivers into the dust collector 41 which 35 comprises a case and cells therein, located preferably on the side of the main case opposite that on which the purifier is arranged.

The fan 39 draws the dust, fluff and other matter from the case 10 and discharges it into 40 the dust collector 41. The dust collector is very similar in its arrangement to the purifier 12 already described, and is provided with slotted sides 42 through which the air may escape. The dust collector has within it a 45 frame 43, which is arranged near the top and is suspended on bolts 44 which project through the top of the collector case and have thumb nuts 45 thereon, so that the tension of the cells 46 suspended from the frame 43 may 50 be conveniently regulated. Any other suitable means may be employed for regulating the tension of these cells, which are identical in their construction with the cells 15 already described, and which, at their lower ends, 55 are attached to a freely moving frame 47 which is normally pulled down, so as to hold the cells taut, by spiral springs 48 attached to the frame 47 and to supports beneath it, but any equivalent things may be substituted 60 for the springs.

Extending transversely beneath the frame 47 is a shaft 49 on which are cams or equivalent vibrators 50 which turn against the frame 47 and which, by so turning, cause the 65 frame to vibrate vertically, thus constantly shaking the cells 46 so as to shake the dust and fluff off of them, while the air passes out

freely through the slots in the side of the case. The shaft 49 may be turned in any convenient way, but as shown, it is driven by 70 a belt 51 extending from a pulley on the shaft to a pulley on the conveyer shaft 52 below it, which shaft is provided with a pulley 53 to which a driving belt 54 may be attached. The dust collector has a hopper-like bottom 75 55, through the lower portion of which extends transversely the conveyer shaft 52, which has the ordinary screw blade 56 thereon, and the conveyer delivers into a spout 57 which may be made to discharge into any 80 suitable receptacle so that the dust, fluff, &c., which settles in the collector, is constantly discharged.

It will be seen from the above description 85 that a continuous stream of stock may be delivered into and discharged from the main case 10, that pure cold air is constantly applied to the stock, that the fluff and dust is effectually separated from the stock, and that this fluff and dust is automatically collected. 90

Having thus described our invention, we claim as new and desire to secure by Letters Patent—

1. An apparatus of the kind described, comprising a main case having a stock inlet at 95 the top, a chute arranged vertically in the case and into which the stock is delivered a hopper like bottom for said case, an air purifier arranged at one side of the case, an inlet pipe receiving air from outside of the building and delivering into a space at the top of the purifier, a pipe leading from one side of said purifier, a fan connected with the said pipe for drawing the air through the purifier, a pipe leading from the fan and delivering 100 to the purified air into the lower part of the main case, and a pipe leading from the upper part of the main case and connecting with an exhaust fan, substantially as shown and described. 11c

2. The combination with the main case having a suitable feed and discharge, of the air purifier comprising a case having a plurality of vertically arranged cloth walled cells located in the central portion of the case, a dust 115 chamber arranged beneath the cells, a space arranged at the top of the case, a pipe leading from said space to the outside air, a pipe leading from one side of the purifier, a fan connected with the said pipe and arranged 120 to draw air through the purifier, and a pipe leading from the fan and discharging the air into the main case, substantially as shown and described.

3. The combination with the main case having a suitable feed inlet and discharge, a depending chute arranged vertically in the case and through which the stock falls, a revoluble agitator arranged in the lower end of the chute, and a revoluble deflector plate arranged below the said vertical chute, of an air purifier receiving out-door air, a fan to draw the air through the purifier, a pipe leading from the fan into the main case and pro-

vided with an upturned closed end located beneath the revolving deflector plate, and air discharge ports arranged in the sides of the upturned end, substantially as described.

5 4. The combination with the main case, the feed chute arranged vertically in the upper part thereof, and the hopper like bottom, of the air pipe delivering into the main case and having the upturned closed end, the air ports 10 arranged in the sides of the upturned end, a casing arranged above the closed end of the pipe, a horizontal shaft held in said casing and provided with a pinion, a vertical shaft extending through the top of the casing, and 15 provided with a pinion meshing with the pinion on the horizontal shaft, a deflector plate carried by said vertical shaft and arranged between the top of the said casing and the lower end of the vertical chute and means for 20 revolving said horizontal shaft, substantially as shown and described.

5. The combination with the main case having a stock inlet and discharge, of the dust collector having slotted sides, an inlet at the 25 top and a hopper like bottom, a transverse carrier leading from the bottom, the cloth walled cells arranged within the case, the ad-

justable supports extending through the top of the case and from which the said cells are suspended, means for vibrating said cells arranged beneath the same, and a fan exhausting from the upper part of the main case and discharging into the dust collector, substantially as described.

6. The herein described dust collector, comprising a case having slotted sides, an inlet at the top, and a discharge hopper at the bottom, a frame arranged within the case near the top thereof, bolts projecting through the top of the case and on which the said frame 30 is suspended, the said bolts being adjustable as set forth, a series of cloth walled cells suspended from the said frame, springs arranged at the bottom of the case to normally hold the cells straight, a screw conveyer in the discharge hopper, a transverse shaft beneath the cells and cams on the shaft arranged to vibrate the cells, substantially as shown and described.
